US00D956391S

(12) **United States Design Patent** (10) Patent No.: **US D956,391 S**
Small et al. (45) Date of Patent: ** Jul. 5, 2022

- (54) **SHOE**
(71) Applicant: **NIKE, Inc.**, Beaverton, OR (US)
(72) Inventors: **Jessica Small**, Portland, OR (US); **Can Eldem**, Portland, OR (US); **Caroline Fullerton**, Portland, OR (US); **Marie Odinot**, Portland, OR (US)
(73) Assignee: **NIKE, Inc.**, Beaverton, OR (US)
(***) Term: **15 Years**
(21) Appl. No.: **29/684,034**
(22) Filed: **Mar. 18, 2019**

Primary Examiner — Garth Rademaker

Assistant Examiner — Laura H Yu

(74) Attorney, Agent, or Firm — Banner & Witcoff, Ltd.

(57) **CLAIM**

The ornamental design for a shoe, as shown and described.

DESCRIPTION

FIG. 1 is a photographic front perspective view of a shoe showing our new design;

FIG. 2 is a side view thereof;

FIG. 3 is an opposite side view thereof;

FIG. 4 is a front view thereof;

FIG. 5 is a rear view thereof; and,

FIG. 6 is a top view thereof.

1 Claim, 5 Drawing Sheets
